E. H. OBERTOP.

CYLINDER COCK.

APPLICATION FILED AUG. 19, 1905

Fig. 1.

UNITED STATES PATENT OFFICE.

EARL H. OBERTOP, OF CHICAGO, ILLINOIS.

CYLINDER-COCK.

No. 839,188.

Specification of Letters Patent.

Patented Dec. 25, 1906.

Application filed August 19, 1905. Serial No. 274,822.

To all whom it may concern:

Be it known that I, EARL H. OBERTOP, a citizen of the United States, residing in the city of Chicago, county of Cook, and State of Illinois, have invented certain new and useful Improvements in Cylinder - Cocks, of which the following is a full, clear, and exact specification.

This invention relates to improvements in cylinder-cocks employed for discharging water from steam-cylinders, and particularly those for railroad-engines, and which have heretofore been actuated by means of an air-pressure cylinder in communication with the air-brake system of a train and connected with the cylinder-cocks by one or more levers pivoted to the piston-rod and to the cam-bar actuating the cocks off and on their seats.

The prime objects of this invention are to dispense with all lever connections between the air-pressure cylinder and the actuating cam rod or bar for the cylinder-cocks and to utilize steam as well as air-pressure for actuating the cocks.

A further object of this invention is to control the supply of exhaust steam and air to the cylinder actuating the cam-bar by the single three-way cock and at such a point that said cock is conveniently accessible to the engineer and whereby at will he may utilize either air from the brake system or steam from the boiler for actuating the cylinder-cocks on and off their seats.

A further object of this invention is to provide means whereby the cylinder-cocks will unseat when either the air-pressure in the brake system or the steam-pressure in the boiler is below the normal pressure either or both are intended to have, and it will be indicated to the engineer by the escape of condensations from the cylinder, owing to the automatic actuation of the cylinder-cocks off their seats by such reduction in pressure.

With these ends in view my invention consists in certain features and novelty in construction, combination, and arrangement of parts by which said objects and certain other objects hereinafter appearing are attained, all as fully described in reference to the accompanying drawings, and more particularly pointed out in the claims.

In said drawings, Figure 1 illustrates a vertical section through a cylinder-cock structure containing my invention, with a detail portion of a cylinder likewise shown; Fig. 2, a side elevation of a railroad-engine boiler,

illustrating the application of my invention thereto; and Fig. 3, an enlarged cross-section of the three-way cock shown in Fig. 2 for regulating the supply and exhaust of both steam and air to the pressure-cylinder directly employed for actuating the cylinder-cocks.

Similar numerals of reference indicate the same parts in the several figures of the drawings.

4 indicates a steam-cylinder of ordinary construction provided with openings 5 5 in its bottom and respectively toward the opposite ends thereof, into which, as shown at the left in Fig. 1, is screwed or otherwise secured a two-part cylinder-cock casing comprising the portion 6, screw-threaded into the cylinder, and the part 7, united by a screw-threaded coil 8, which when secured in its operative position impinges against a flange 65 surrounding the part 6 and is screw-threaded upon the part 7. In and between this two-part casing and formed partly in each is a cone-shaped chamber 9, forming a receptacle for condensations when the valve 10 is on its 70 seat 11, formed in the part 7 of the casing, but which affords a passage through which condensations in the cylinder are conducted in their discharge from the cock.

The valve 10 is provided with a stem 12, 85 surrounded by an enlarged chamber 13, opening outwardly from the casing 7 at 14, and has on its lower end an elongated weight 15, passing through the lower portion of the casing 7 into a chamber 16, formed in the end 90 wall 17 of a cylinder 18 and adapted to engage by gravity with a piston-rod 19, on which is a piston 20 and a coiled spring 21, the latter surrounding the piston-rod at a point between the piston and the end of the 95 cylinder and by its expansion tending to maintain the piston in the position shown in Fig. 1 and the cylinder-cock in an elevated position above its seat.

The piston-rod 19 is provided with cut-away portions 22, providing cam-surfaces 23, by means of which the valves and the cylinder-cock are unseated, as shown in Fig. 1, and also seated when the valve-rod is moved forward in the direction indicated by the arrow in said figure by means presently to be described.

Instead of the specific construction of valve-cock shown in Fig. 1—that is to say, in which the valve seats inside the shell of the 110 valve-cock—said valve may be projected beyond the inner end of said shell and have its

seat externally of the shell, and said seat may be formed in a suitable plate 24, secured to the end of a shell, which, as shown, may be entirely in one piece with an enlarged continuous chamber surrounding the thereby necessarily elongated valve-stem 12 and terminating in the outlet 14, the stem being provided with a weight 15, corresponding with that shown in the structure at the left of Fig. 1 and adapted to engage and be actuated by the piston 19 in precisely the same manner as the structure first described.

The cylinder 18 is provided with a screw-threaded cap 25, having a central perforation 26, and into which and registering with the perforation 26 is a pipe 27, which (see Fig. 2) extends upwardly preferably above the running-board 28 of an engine, and a horizontal extension opening into the shell 29, in which is the plug 30 of a three-way cock, which is also connected with the air-brake system (not shown) of a railroad-train by a pipe 31 and with the steam-boiler by the pipe 32; in which is an ordinary stop cock or valve 33, (see Fig. 2,) a pipe 34 at a point between the pipes 27 and 32 serving as a discharge-outlet for both steam and air when released from the cylinder 18, as hereinafter described, which pipe 34 preferably extends downwardly and has its discharge-opening at a point below the boiler or the ash-box thereof, as indicated in Fig. 2.

In the plug 30 are three radial passages 35, 36, and 37 in common communication with each other, as shown at the axis of the plug, but may be at any other point within the confines thereof, the passage 35 being for the purposes of connection with the steam-supply pipe 32, the passage 36 for connection with both the air-pipe 31 and the cylinder-supply pipe 27, and the passage 37 for communication with both the cylinder-supply pipe 27 and the discharge-pipe 34.

The passages 36 and 37 are enlarged at their outer ends instead of, as may be, having them throughout their length of their present greatest diameter.

The pipe 31 is coupled to a pipe 40 (see Fig. 2) of the air-brake system of a railroad-train or other system, preferably at a point between the usual valve 41, controlled by the lever 42 and the air-reservoir on the engine, and the spring 21 is so adjusted that a pressure of, say, fifty or sixty pounds will compress it and force the piston 20 to the limit of its forward stroke and move the piston-rod until the weighted ends of the valves pass downwardly off the cam 23 and the valves are seated.

In the operation of the device as indicated by the position of the triple cock in Fig. 3 the piston-cylinder is in open communication with the steam-pipe 32 and supposedly with the boiler through the opening of the valve 33, with the result that if the pressure

in the steam-boiler is above sixty or seventy pounds pressure, or whatever pressure the spring 21 is adjusted to, such spring is compressed and the piston and its rod 19 are at the limit of their forward stroke and the valves 10 of the cylinder-cock seated; but if while in this position the steam-pressure in the boiler is reduced below that for which the spring 21 is set the spring will then expand and force the piston 20 and its rod 19 to the limit of their backward strokes, with the result that the valves 10, through their rods 12 and weights 15 and the cams 23 on the piston-rod, will be forced upwardly off their seats, and thereupon water in the cylinder will be discharged through the cylinder-cocks and downwardly from their discharge-openings 14, and said valves will not again seat until the piston is subjected to a steam or other pressure above that for which the spring is set. When, however, there is the continuous higher pressure in the boiler and it is desirable to in the meantime unseat the valves and discharge water from the cylinder, the plug 30 of the three-way cock is turned in the direction indicated by the arrow in Fig. 3—that is to say, until the way 35 has passed beyond register with the steam-pipe 32 and the ways 36 and 37 are respectively in register with the pipes 27 and 34, whereupon the steam in the cylinder 18 will discharge through the ways 36 and 37 and thence outwardly into the air through the pipe 34. Preferably, however, the piston 20, its spring 21, and rod 19 are preferably actuated by air for seating and unseating the valves of the cylinder-cocks, for the purposes of which operation steam through the pipe 32 is cut off by closing the valve 33, and the plug 30 of the three-way cock is turned in the opposite direction until the ways 36 and 37 are respectively in register with the pipes 31 and 27. If while in the above position the air-pressure in the engine-reservoir or from any source is above that for which the spring 21 is adjusted, the spring will be compressed and the piston and piston-rod will be at the limit of their forward stroke and the valves of the cylinder-cocks seated and remain seated until the happening of one of two things—namely, a reduction in pressure in the air-reservoir below that resisted by the spring or the turning of the plug 30 of the three-way cock until the ways 36 and 37 are respectively in register with the pipes 27 and 34, and whereupon and on the escape of the air from the cylinder out through the pipe 34 the spring will expand, the piston and its rod will move to the limit of its backward stroke, and the valves of the cylinder-cock move to their unseated position. (Shown in Fig. 1.)

From the foregoing it will be obvious that with the tension of the spring so adjusted that it will expand when the pressure in the

reservoir is reduced below the minimum pressure it is designed to have the valves will not only be automatically actuated, but the discharge from the cylinder-cock will serve as a signal notifying the engineer that his pressure is too low. Again, if the pipe connecting the air-pump with the main reservoir becomes gummed up and the pump is working hard, the engineer will be warned by the discharge from the cylinder-cock that he is not getting the proper pressure and that his pump is working against its own pressure and perhaps running hot and burning. In event the locomotive should lose its air in the main reservoir the engineer will likewise be warned that his air is gone, assuming that the gage registers properly, but in reality is stuck and needs testing.

When steam to the exclusion of air is employed for actuating the cylinder-cocks, as before described, both cylinders should be connected by a steam-pipe with the boiler and, as may be, by a branch (not shown) extending from pipe 27, Fig. 2, to the cylinder on the opposite side of the engine. When using steam, the reduction or cutting off the steam-pressure operates precisely the same as the air to automatically open the cylinder-cocks. It is therefore obvious that as soon as a locomotive is run into a roundhouse the pressure is released from back of the piston in the cylinder-cock, the valves of the cylinder-cocks will be open, and any condensation in the cylinders will be discharged therefrom, and thereby prevent the freezing up and breaking of the steam-cylinder. Furthermore, when the air-pressure is below a certain point—say sixty or seventy pounds—the cylinder-cocks will be open, with the result that the engine will be prevented from running away in case of a leaky throttle.

Aside from the use of the three-way cock the operation of the cylinder-cocks to their piston necessitates the employment of but a single pipe running from the cylinder-cock to the engine-cab and connected with the main-reservoir pressure at the brake-valve and

providing said pipe with a cock or valve, so that it may be cut in or out, as occasion requires.

My improved cylinder-cock may also be operated by steam-pressure through a branch pipe running from the boiler-head to the air-pipe and for substitution in case the air-pressure fails.

When applied to simple engines, two improved cylinder-cocks are employed, but for a compound engine four should be used.

Having described my invention, what I claim, and desire to secure by Letters Patent, is—

1. A cylinder-cock comprising in combination valves seating by gravity, a cylinder, a piston, a piston-rod, cam-surfaces on said rod directly engaging said valves, and a spring actuating said piston-rod in one direction, substantially as described.

2. A cylinder-cock structure comprising in combination weighted valves seating by gravity, a cylinder, a piston and a piston-rod provided with cam-surfaces and adapted to actuate said valves off and on their seats, a pipe connection therefor with steam and air pipes and a three-way cock controlling the supply of air or steam to said cylinder and their discharge therefrom, substantially as described.

3. A cylinder-cock structure comprising in combination weighted valves seating by gravity, a cylinder, a piston-rod provided with cam-surfaces directly engaging and actuating said valves, a spring actuating said rod in one direction, a three-way cock, a pipe connection between said cock and cylinder and means for supplying steam or air alternately to said cock and whereby the supply to and discharge from the cylinder may be controlled and regulated, substantially as described.

EARL H. OBERTOP.
